UNITED STATES PATENT OFFICE.

DAVID E. HOWATT, OF EAST CLEVELAND, OHIO.

DITCHING-MACHINE.

954,677.

Specification of Letters Patent. Patented Apr. 12, 1910.

Application filed May 12, 1904, Serial No. 207,560. Renewed May 17, 1906. Serial No. 317,346.

To all whom it may concern:

Be it known that I, DAVID E. HOWATT, a citizen of the United States, resident of East Cleveland, county of Cuyahoga, and State of Ohio, have invented a new and useful Improvement in Ditching-Machines, of which the following is a specification, the principle of the invention being herein explained and the best mode in which I have 5 contemplated applying that principle, so as to distinguish it from other inventions.

My invention relates to machines for excavating the soil to form ditches for tiling in land drainage, such machines being commonly referred to as "ditching machines."

Said invention has for its object the excavation of such ditches with the removal of a minimum amount of earth; in other words, my improved form of ditching machine is 20 designed to excavate a narrow ditch or trench with substantially vertical sides to whatever depth, within usual limits, it is desired to go. This result, I am aware, has been achieved heretofore, by means of the 25 entirely different and much more cumbersome and expensive type of machine in which the excavating is accomplished by plows or shovels attached to or in combination with suitable elevating or conveying 30 means.

My machine utilizes as the earth-detaching means a pair of rotary disks whose axes of rotation are inclined to each other, and my invention embodies the principle which 35 controls the operation of such disks. This principle, briefly stated, is that to accomplish the excavation of a ditch with vertical sides by means of two disks as described above, the plane passing through the axes of 40 rotation of such disks must be approximately horizontal no matter at what depth such disks may be operating. The reason for this is obvious: The disks cut effectively and form vertical sides only when the point 45 where they most nearly approach each other is directly in the rear. Now, the greater the depression of the plane passing through the axes of said disks from the horizontal, the greater will be the loss in efficiency and the 50 more inclined the sides, until such point of nearest approach of the disks is directly below, the disks will not cut at all and the bottom of the ditch be narrowed to a line. With a view to obviating this difficulty, and 55 the accomplishment of other desirable objects, said invention then consists of the

means hereinafter fully described and particularly pointed out in the claims.

The annexed drawing and the following description set forth in detail certain mechanism embodying the invention, such disclosed means constituting but one of various mechanical forms in which the principle of the invention may be used.

In said annexed drawing: Figure 1 represents a plan view of a ditching machine embodying my invention, with the conveyer removed; Fig. 2 represents a broken side elevation of such machine; Fig. 3 represents a partial end elevation looking in the direction indicated by the arrow in Fig. 1; and Fig. 4 represents a detail cross-section taken upon the plane indicated by the line IV—IV on Fig. 1.

The said device consists primarily of two 75 main parts, a carriage and a pivotal frame carrying excavating means and a conveyer, as will be presently described. The carriage proper comprises two wheels A A mounted upon a suitable axle B; two upwardly 80 curved, rearwardly extending iron bars B' B' that form the body of the carriage, such bars being journaled at their front ends upon the axle and secured to each other at their rear ends by a cross-plate b; and a 85 swiveled wheel, or trailer, b' that is journaled in said plate b. Braces b² b², b⁷ b⁷ are secured as shown to stiffen the structure of the carriage body. A plate C is secured to the top of said bars and affords a seat for 90 the driver. In the rear of such seat is mounted a drum C' journaled in suitable standards b³ b³, and provided with a hand wheel b⁴, ratchet-wheel b⁵ and dog b⁶ engaging said ratchet-wheel, whereby a chain 95 C² may be wound upon said drum as will be readily understood.

The pivotal frame referred to above comprises two side plates d d journaled upon axle B, to the upper end of which are secured respectively two rearwardly extending parallel iron or steel bars d'; a trough d² being attached to the rear ends of the latter; and a lower angle-bar d³ whose front end is secured to the plates d d by means of a 100 transverse rod d⁴ passing through such plates, and whose rear end is riveted to the bottom of the front end of trough d² as shown. A yoke d⁵ is secured to the trough to which is attached the lower end of chain 105 C², whereby it is seen, the rear or free end of the frame is suspended from the carriage 110

and may be raised or lowered by means of the hand-wheel b^4 and drum C'.

In the upper portions of plates d d is journaled a spindle e of a rotary drum E, which 5 spindle carries two sprockets e' e' on opposite sides of the drum respectively, which are driven by two chains e^2 e^2 themselves driven by two sprockets e^3 e^3 secured to axle B. In the rear end of trough d^2 is mounted 10 a second rotary drum e^4 and around this drum passes a belt f carrying means for catching and holding soil, forming a traveling conveyer, the upper portion of which travels from rear to front, the side bars d' 15 forming a guide for same. Such catching and holding means I have shown to consist of buckets f' . The angle-bar d^3 supports the lower or return portion of the conveyer and prevents same from sagging. The trough 20 d^2 , having bottom and sides, protects the lower end of the conveyer and prevents the same from coming into contact with the ground as the machine passes over it.

At the rear extremity of the frame is 25 mounted the means for excavating or detaching the soil. Such means comprise a device for raising the soil and discharging the same onto the conveyer belt just described, and consist of two rotary disks G G mounted 30 upon studs g g secured to the end and outside of the trough d^2 , the axes of said studs being inclined relatively to each other, as shown. These disks plow through and 35 detach the soil and drop it upon the conveyer so that the buckets f' of the latter catch the same easily, without the necessity of its being pressed or forced therein, and then carry it forward to the front of the machine. Disks G G may be adjusted by 40 being moved up and down by means of the chain, drum and hand-wheel before mentioned. A rearwardly projecting shoe d^6 is secured to the bottom of the end of the trough d^2 , which protects such end from 45 wear and also assists in loosening up the soil with which it comes in contact. At the front of the carriage and below the front end of the conveyer is a trough or chute H which inclines laterally, receives and 50 discharges the soil discharged from the conveyer as will be readily understood.

In operation, the above described machine is drawn along over the ground to be ditched, the rotation of wheels A effecting 55 the operation of the conveyer. The disks are dropped a distance determined by experience to effect the excavation most efficiently in view of the character of the soil at the scene of operation, the trailer b' following on behind in the ditch and supporting the rear end of the body. The trough H is fastened at an angle such that the jar of the machine while in operation will suffice to insure the discharge of the soil therefrom. If the excavator strikes a stone or

other obstacle too large to be included between the disks G G, it is not necessary to stop the machine, pull or push it back for a distance, and then lift it over the obstacle, but my arrangement of disks and the suspended condition of one end of the pivoted frame permit the disks to ride easily over such obstacle without injury to the machine or a loss of time. The trough d^2 also acts as a protection to the lower part of the frame, as well as the protecting shoe d^6 , and assists the disks in riding easily over the obstacle when the latter gets in under the trough. It will also be seen that the adjustable feature of said frame permits 75 ditches of varying depth to be excavated, it being only required to repeat the operation over the same path, each successive operation being accompanied by a lowering of the free end of the frame and disks mounted 80 thereon. It will also be clear that in view of the elongation of the frame, so that its length, or radius of oscillation largely exceeds the radius of the excavating disks, the latter may be depressed to a considerable 85 depth and yet involve only a relatively small angular movement on the part of the frame. The angle that the axes of said disks will be depressed from the horizontal plane in which they should lie will be correspondingly small and their cutting efficiency hence not perceptibly decreased.

In the form of machine described above, the result to be attained, *i. e.* the maintaining of the plane passing through the axes 100 of rotation of the disks substantially horizontal is accomplished by such a proportioning of the parts of the machine as will require the swinging of the pivotal frame through only a small angle from the horizontal in order to depress its free end, and the attached disks, to a considerable depth. The condition involved may be, perhaps, best expressed in terms of the relationship 105 between the radius of the rotary disks G and the radius of the arc of the circle in which they are swung.

Other modes of applying the principle of my invention may be employed instead of the one explained, change being made as 110 regards the mechanism herein disclosed, provided the means stated by any one of the following claims or the equivalent of such stated means be employed.

I therefore particularly point out and 115 distinctly claim as my invention:

1. In a ditching machine, the combination of a carriage; a secondary frame having one end pivoted to and the other end suspended from said carriage; excavating means mounted upon said frame and consisting of two rotary disks having their axes of rotation inclined to each other; and means for conveying and elevating excavated soil, said carriage and excavating 120

means being so disposed and proportioned relatively to each other as to maintain, within the working limits of the machine, the axes of rotation of said disks in a substantially horizontal plane.

2. In a ditching machine, the combination of a carriage; a secondary frame having one end pivoted to and the other end suspended from said carriage; a conveyer mounted upon said frame; and rotary disks, whose axes of rotation are inclined to each other, mounted upon said frame, adapted to excavate soil, and discharge the same onto said conveyer.

15 3. In a ditching machine, the combination of a carriage; a secondary frame having one end pivoted to and the other end suspended from said carriage; means for raising and lowering the suspended end of said frame; a conveyer mounted upon said frame; studs, whose axes are inclined to each other, secured to said frame; and means carried by said studs, adapted to excavate soil, and discharge the same onto said 25 conveyer.

4. In a ditching machine, the combination of a carriage; a secondary frame having one end pivoted to and the other end suspended from said carriage; means for raising and 30 lowering the suspended end of said frame; a conveyer mounted upon said frame; studs secured to the suspended end of said frame and having their axes inclined to each other; disks carried by said studs, adapted to excavate soil, and discharge the same onto said 35 conveyer; and means secured to said frame and adapted to assist its suspended end in riding over obstacles and to protect said conveyer from contact with the soil.

40 5. In a ditching machine, the combination of a carriage; excavating means carried thereby; a conveyer inclining upwardly from said excavating means in the direction in which said machine is designed to move; adapted to elevate and carry excavated soil away from said means; and a trough in which said conveyer is guided and protected from contact with the soil, said excavating means being adapted to place the excavated soil in said trough.

45 6. In a ditching machine, the combination of a carriage; excavating means carried thereby; and a conveyer inclining upwardly from said excavating means in the direction in which the machine is designed to move, adapted to elevate and carry excavated soil away from said means, said excavating means being adapted to place the excavated soil in position to be thus operated upon by 50 said conveyer.

60 7. In a ditching machine, the combination of a carriage; excavating means carried

thereby; a conveyer for carrying excavated soil away from said means; a trough positioned under said conveyer and in which the latter is guided, said trough protecting said conveyer from contact with the soil; and a protecting shoe carried upon one end of said trough and adapted, in combination with the latter, to enable said excavating means to ride over obstacles.

8. In a ditching machine, the combination of a carriage; a secondary frame pivotally mounted upon said carriage; rotary disks whose axes of rotation are inclined to each other, mounted upon said frame and adapted to excavate soil; and means movable with and by said carriage, mounted upon said secondary frame, and adapted to receive and convey excavated soil away from said disks.

9. In a ditching machine, the combination of a carriage; rotary disks whose axes of rotation are inclined to each other, suspended from said carriage and adapted to excavate soil; means for vertically adjusting said disks; and means for receiving and carrying the excavated soil away from said disks.

10. In a ditching machine, the combination of a carriage; a frame having one end pivoted to and the other end suspended from said carriage; a conveyer mounted upon said frame; means for vertically adjusting the suspended end of the latter; and two cutting members adapted to excavate soil, elevate the same intermediately of their contiguous surfaces, and discharge it onto said conveyer.

11. In a ditching machine, the combination of a carriage; a secondary frame pivotally mounted upon said carriage; disks rotatably mounted on the free end of said frame and adapted to detach the soil, the axes of said disks being inclined to each other and the axis of oscillation of said frame being higher than that of said axes; and means mounted upon said frame for receiving such soil from said disks and conveying the same away.

12. In a ditching machine, the combination of a carriage; a secondary frame pivotally mounted upon said carriage, and inclining downwardly therefrom; disks rotatably mounted on the free end of said frame and adapted to detach the soil, the axes of said disks being inclined to each other; and means mounted upon said frame for receiving such soil from said disks and conveying the same away.

Signed by me, this 10th day of May, 1904.

DAVID E. HOWATT.
